CABLE TIED SPRING UNITS

Huot Walter Sternberg, Westport, Conn., assignor
to The Owen Silent Spring Company, Inc.,
Bridgeport, Conn., a corporation of Connecticut

Application September 20, 1940, Serial No. 357,542

3 Claims. (Cl. 5—267)

This invention relates to improvements in spring units and more particularly to improvements in ties and in clips for connecting the ties to upstanding helical springs.

In well known constructions adjacent upstanding helical springs and wire ties are secured together by clips. These constructions are not entirely satisfactory as the wire ties break after a certain amount of use and in certain instances the wire ties work out through the cover at an edge of the cushion into a position to cause injury.

Among the objects of this invention is the provision of ties in the form of twisted wire strands or cables (herein referred to as cables) so connected to adjacent springs as to give increased life to the ties and therefore to the cushion, and to provide a more flexible construction.

Other objects of this invention will appear from the following description taken in connection with the drawing in which:

Fig. 1 shows a top plan view partly broken away of a spring unit equipped with cable ties;

Fig. 2 is an enlarged top plan view of portions of adjacent springs, a section of a cable tie, and a clip connecting the same together;

Fig. 3 is a transverse vertical section on the line 3—3 of Fig. 2;

Fig. 4 is a longitudinal vertical section on the line 4—4 of Fig. 3; and

Fig. 5 is a section corresponding to Fig. 4 showing a clip with relieved ends.

In Fig. 1 is disclosed a cushion unit comprising upstanding or vertical helical springs 6, the ends of the upper convolutions of which may be free and preferably bent downwardly or may be knotted to the next lower convolution as is well understood. The cushion unit may be surrounded by a wire frame 7, if desired. As disclosed in this figure, I employ cables 8 as ties which are interposed between and in the horizontal plane of the upper convolutions of the helical springs and as disclosed more particularly in Figs. 3 and 4, the cables are preferably of smaller diameter than the diameter of the wire from which the springs are formed. The cable and adjacent springs are secured together by an encircling band clip 10 which surrounds the wire of the springs and the cable, the ends of the clip being folded upon each other as indicated at 11.

The clip is secured to the springs and cable by indenting the upper wall of the clip as at 12 which produces a projection which has a diameter substantially the same as that of the cable and which may be and preferably is of a length

to flatten the cable as indicated at 13 to frictionally grip the cable and to spread the cable laterally into tight frictional contact with the springs to hold the clip, cable and springs fixedly secured together. By using a cable of smaller diameter than that of the wire from which the springs are formed, a certain amount of free vertical movement of the cable within the ends of the clip is permitted as indicated in Fig. 4 by the spaces 14 so that adjacent springs may be depressed without producing a cutting action by the ends of the clip on the cable. The cable is thus securely anchored against longitudinal movement in the clips and against rotation in the clips and the tendency to rotate is also reduced by the fact that the length of the cable between adjacent clips is angularly yieldable so that rotation given to one end of such length by the depression of adjacent springs will not be transmitted to the other end of such length in the next adjacent clip. The springs are tied together in an efficient manner by the cables. While the cables possess the desired amount of flexibility, they are of sufficient rigidity to hold adjacent springs spaced apart.

In applying the clip I may use dies so formed that the clip will take the shape disclosed at 15 in Fig. 5, in which the upper wall 17 of the clip is of arcuate form, that is, the openings 15 in the ends of the clip are relieved or flared upwardly so that two adjacent springs may be compressed a considerable amount before the upper wall of the clip engages the cable thus preventing the clip from cutting the cable or bending the cable about the edge of the clip which would cause the cable to break.

By means of this invention I have provided a construction in which the ties provide a very flexible cushioning unit and in which there is no danger of injury due to ties working out through the side of the cover of the cushion. These ties have been found to last several times longer than the usual wire ties. As the frictional engagement of the ties with the springs provides for locking the ties against longitudinal movement relative to the springs, it will not be necessary to indent the clip on the springs as in certain prior constructions.

While I have described two modifications of my invention it is to be expected that changes and modifications may suggest themselves to those familiar with this art after understanding my invention and it is to be understood that I reserve the right to all such changes as fall with-

in the principles of this invention and the scope of the appended claims.

I claim:

1. In a device comprising two wires and an interposed twisted wire cable in juxtaposition in a common plane, and a clip surrounding said juxtaposed wires and cable and indented at a point centrally of its length upon the cable, said indenting being of sufficient depth to flatten said cable and to spread the same laterally into frictional holding engagement with said wires, and said cable being of smaller diameter than said wires whereby freedom of movement of said cable within the ends of said clip at right angles to said plane will be permitted.

2. In a device comprising three elements in juxtaposition in a common plane, and a clip surrounding said juxtaposed elements indented at a point centrally of its length upon the middle one of said elements, said middle element comprising a twisted wire cable and the outer elements comprising single wires and said indenting being of sufficient depth to flatten said cable and to spread the same laterally into frictional holding engagement with said wires, and said cable being of smaller diameter than said wires whereby freedom of movement of said cable within the ends of said clip at right angles to said plane will be permitted.

5. In a device comprising two wires and an interposed twisted wire cable in juxtaposition in a common plane, and a clip surrounding said juxtaposed wires and cable and indented at a point centrally of its length upon the cable, said indenting being of sufficient depth to flatten said cable and to spread the same laterally into frictional holding engagement with said wires, and said cable being of smaller diameter than said wires, the wall of the clip in which the indentation is formed being of an arcuate form with its center on the same side of the clip as the indentation.

10. In a spring cushion comprising parallel rows of helical wire springs, cable ties interposed between adjacent portions of the terminal convolutions of adjacent springs of adjacent rows, said ties being of shorter diameter than the diameter of the wire stock from which the springs are formed, and clips surrounding said ties and said portions of said springs and secured to said ties and said portions of said springs by indentations impressed in the portions of the clips overlying the outer faces of said ties, producing projections in frictional wedging engagement with said portions of said springs and in compression engagement with said ties, flattening and spreading said ties into frictional engagement with said portions of said springs.

HUOT WALTER STERNBERG.
